UNITED STATES PATENT OFFICE.

JOHN J. TATUM, OF BALTIMORE, MARYLAND.

COUPLER STRIKING PLATE.

Application filed October 3, 1923. Serial No. 666,287.

My invention relates to coupler striking plates.

Among the objects of my invention are:

To produce a coupler striking plate which 5 can be formed of bar metal and which will be lighter, stronger and cheaper than those now in use which are usually formed of cast steel.

To produce a coupler striking plate which 10 will strengthen the end of the car near the coupler.

To produce a coupler striking plate having a portion located to receive the impact of the coupler horns, which portion is reenforced in order to resist the impact without 15 deformation or fracture.

To provide a coupler striking plate having a removable wearing piece to support the coupler so that the main members of the 20 striking plate will be entirely free from wear.

These and other objects of my invention and the means by which they are effectuated will be set forth in the following specification, reference being had to the accompanying 25 drawings, and the novel elements, combinations of elements and features of my invention will be definitely pointed out in the claims.

30 In the drawings:

Figure 1 is a partial end view of a car body showing my improved striking plate applied thereto.

Fig. 2 is a view of the striking plate shown 35 in Fig. 1 looking in the direction of the arrow 2 in said figure.

In the figures the outline of the coupler is shown dotted.

In the drawings:

40 5 is a portion of the end sill of the car body and to said sill the flat portions 6 and 7 of my improved striking plate are secured by rivets such as 8.

Between the portions 6 and 7 is the channel-shaped portion 9 which receives the impact of the horns 10 of the coupler 14 and thus limits in one direction the endwise movement of the latter. In order to strengthen the projection 9 so that it may 45 resist the impact of the coupler without deformation or fracture, the channel shaped re-enforcing member 11 is mounted within said projection and the ends of said member bear upon the plate 5 of the end sill.

50 55 The member 11 is secured within the projection 9 by rivets such as 12.

The portion 7 is cut away at its center in order to provide an opening 13 for the passage of the coupler 14 and each part of the portion 7 is provided with an out-turned striking flange 15 which receives the impact of the coupler 14 and thus limits the sidewise movements of the latter.

Each part of the portion 7 is provided with an out-turned supporting flange 16 which supports the vertical limb of the angle iron 17. The angle iron 17 is riveted to the parts of the portion 7 by rivets 18 and said iron thus secures the two parts of the portion 7 together.

Upon the horizontal limb of the angle iron 17 there is mounted a wearing plate 19 formed of channel iron upon which rests the body of the coupler 14.

My improved striking plate having the 75 projection 9 and the re-enforcing member 11 in proximity to the cut-away portion of the end sill plate 5, it is evident that said projection and member greatly strengthen said end sill.

It is also evident that by placing the member 11 within the projection 9 I prevent the latter from being fractured or deformed by stresses applied thereto by the coupler.

By providing the flange 16 to support the lower limb of the angle iron 17, I relieve the rivets 18 from vertical stresses imposed by the coupler 14 and thus prevent shearing of said rivets.

By the provision of the wearing plate 19, I 90 ensure that the angle iron which supports the coupler 14 will not be worn by the movement of the latter and provide that a new wearing surface can be readily supplied by the replacement of the plate 19.

As the coupler 14 moves from side to side, as when the car is rounding a curve, the coupler will strike either of the flanges 15, which will thus limit the movement of said coupler within the opening 13. The impact 100 of said coupler upon the flanges 15 will be resisted by the bending moment of the parts of the portion 7 aided by the angle iron 17 which secures said parts together.

Thus it will be seen that I provide a coupler striking plate which is simple in construction, has great strength where excessive forces may be applied and provision for preventing wear upon a part which would otherwise be subject to the abrading action 105 of the coupler body.

While I have shown one preferred shape

for the elements and one preferred combination thereof, it is to be understood that the disclosure is for illustrative purposes only and in no wise to limit the scope of my 5 invention.

I claim:—

- 10 1. A coupler striking plate, adapted for attachment to the end sill of a car, comprising a channel-shaped projection for receiving the impact of the coupler, a pair of spaced depending portions having flanged ends defining an opening for the passage of said coupler, said ends extending along the width of said portions, and an angle iron 15 resting on said flanged ends and secured to said portions for supporting said coupler.
2. A coupler striking plate, adapted for attachment to the end sill of a car, comprising

ing a channel-shaped projection for receiving the impact of the coupler, and a channel-shaped reinforcing member mounted in said projection. 20

- 25 3. A coupler striking plate, adapted for attachment to the end sill of a car, comprising a channel shaped projection for receiving the impact of the coupler, a pair of spaced depending portions having flanged ends defining an opening for the passage of said coupler, an angle iron resting on said flanged ends and secured to said portions for 30 supporting said coupler, and a channel shaped reinforcing member mounted in said projection.

In testimony whereof, I affix my signature.

JOHN J. TATUM.
